UNITED STATES PATENT OFFICE.

CHARLES M. MCGOWEN, OF ST. LOUIS, MISSOURI, ASSIGNOR OF ONE-HALF TO
JOHN B. MARTIN, OF SAME PLACE.

WASH-BOILER.

SPECIFICATION forming part of Letters Patent No. 442,533, dated December 9, 1890.

Application filed July 18, 1890. Serial No. 369,166. (No model.)

To all whom it may concern:

Be it known that I, CHARLES M. MCGOWEN, of St. Louis, in the State of Missouri, have invented certain new and useful Improvements 5 in Steam-Washers, of which the following is a full, clear, and exact description, reference being had to the accompanying drawings, forming a part thereof.

My invention has for its object to provide 10 a novel and simplified construction in steam-washers; and it consists in the combination and arrangement of parts, as will be herein-after fully described, and designated in the claims.

15 In the drawings, Figure 1 is a vertical longitudinal section of my invention, taken on the line $x-x$ of Fig. 2. Fig. 2 is a top plan view of the same. Fig. 3 is a side elevation partly broken away, and Fig. 4 is a vertical longitudinal section of a modification of my invention partly broken away.

20 The object of my invention is to produce a clothes-washer that will direct the water contained therein through the clothes from the bottom thereof, obtaining from the water in this state the most effective washing qualities.

25 Referring to the drawings, 1 represents a boiler of cylindrical form, having an annular flange 2 formed around the same at a suitable distance from the top thereof, and which forms a seat or resting-place for the removable combined cover and overflow, as hereinafter described.

30 The boiler 1 is provided with an opening 3, 35 extending from the annular flange 2 to the top thereof, and which leads to a tapering tube 4, fastened to the said boiler, by means of which the water is carried back into the lower portion of the boiler, from whence it came, to be again washed through the clothes. The larger portion of the tube is located on the outside of the boiler and in contact with the opening 3, the said tube leading downward and bent at 5 and passing through an opening

40 45 50 55 60 65 70 75 80 85 90 95 100

ing 6, formed in the lower portion of the boiler, or near the bottom thereof. The projecting end 7 of the tube extends some distance within the boiler, and is provided with an inclined face 8, which forms a resting-place or

of the tube 4 is hinged a valve 9, and which rests upon the inclined portion or face 8 by gravity, allowing the water, after being forced through the clothes, to pass again in the boiler, and preventing the same from being forced up through the said tube.

10 represents lugs fastened to the interior cylindrical surface of the boiler and at a suitable distance from the bottom thereof, and upon which lugs a removable perforated plate 60 or wire-netting 11 rests for supporting the same, and upon which the clothes rest when placed in the boiler.

The combined cover and overflow 12 is provided with an opening 13 at its center, and 65 around said opening is formed an annular flange 14, which prevents the water from returning after being forced through the said opening.

In the modification shown in Fig. 4 a wire 70 ring 15 is substituted in place of the annular flange 2 and provides a seat for the combined cover and overflow 12; also a ring 16 is fastened to the boiler and is substituted in place of the lugs 10, and which acts as a seat for the 75 perforated plate or wire-netting 11.

Any quantity of water is first placed in the boiler and the clothes placed in the same upon the perforated plate 11, and the combined cover and overflow 12 placed in position, as 80 shown in Fig. 1.

When the boiler is placed upon the stove and properly filled with water and clothes, the said water, when in a boiling condition, will be forced direct through the clothes, as shown 85 by the arrows, and passes through the opening formed in the combined cover and overflow, and from thence it flows to the tube 4, which tube directs the said water back into the boiler below the clothes. The valve located at the 90 extreme lower end of the tube prevents the water from rising through the same, and by so doing the said water will be forced through the clothes in a highly-heated state.

I am aware that prior to my invention side 95 tubes, perforated bottoms, and valves have been used, and the water forced first through the tubes and from the said tubes is directed upon the clothes in the boiler, and do not therefore claim, broadly, these elements. 100

In a large boiler two passages such as described may be attached to the boiler, and which will operate in the manner as heretofore stated.

Having fully described my invention, what I claim is—

1. An improved steam-washer consisting of a chamber, a perforated plate or wire-netting located therein, a combined cover and overflow located above the said perforated plate, an opening formed in the said cover, through which the water passes, a tube fastened to the said boiler and in communication therewith, the lower end of which enters the boiler below the perforated plate, and a valve located on the extreme lower end of the said tube, substantially as described.
2. In a steam-washer, the combination of the boiler 1, having the annular flange 2 formed therewith, the perforated plate 11, lo-

cated therein and resting upon the lugs 10, the combined cover and overflow 12, resting upon the said annular flange and provided with the opening 13, the tube 4, connected with an opening 3 in the boiler, the lower portion of the said tube being bent and passed through an opening formed in the said boiler below the plate 11 and being formed into an inclined valve-seat, and the valve 9, resting on said inclined valve-seat and adapted to automatically admit water from the tube to the boiler and to prevent its flowing in the opposite direction, substantially as described.

In testimony whereof I affix my signature in presence of two witnesses.

CHARLES M. McGOWEN.
